ABSTRACT: A linear time display clock in the form of a column having a translucent face behind which is a vertical stack of 11 cells. Electric bulbs in the cells are selectively activated by an electrical control circuit operated by a timer, whereby the cells are sequentially illuminated to provide a colored panel on the face of the column whose position is indexed linearly to indicate the passage of time. The hours one to 11 are indicated by illumination of cells one to 11, respectively, going from top to bottom, whereas the 12th hour (noon and midnight) is indicated by again illuminating the sixth or midpoint cell, the distinction between the sixth and 12th hour being established by a difference in panel color. Five-minute increments, which are 11 in number, running from five minutes to 55 minutes, are indicated by sequentially illuminating cells one to 11, but in a color distinct from the hour indications.

LINEAR TIME COLUMN

BACKGROUND OF INVENTION

This invention relates generally to timepieces, and more particularly to a clock in the form of a column having a linear time display.

In conventional clocks, the time display is almost invariably in the form of hands which turn at different rates to afford hour and minute indications. The appearance of a standard clock, however modern its casing and however streamlined or stylized its time display, is nevertheless incongruous in a contemporary setting. The current trend toward minimal art in architecture and in interior design involves a reduction in apparent detail in order to establish an environment in which mechanical, structural and electronic elements are obscured or submerged. Existing clocks fail to meet the criteria for minimal art.

Living in a highly advanced technology in which individuality has little place, the individual, in order to regain his equilibrium and sense of personal worth, seeks in his domestic environment to avoid the appearance of complexity without, however, sacrificing engineering advantages. Thus, it is often the practice to house stereophonic high-fidelity equipment in cabinets of extreme simplicity having a so-called black light panel, which, in the absence of internal illumination, presents a perfectly blank mirrorlike surface concealing the underlying dials and meters.

In minimal art, furnishings take the form of basic geometric shapes, such as slabs, cubes, cylinders and parallelepipeds, the shapes being adapted to function as beds, seats and sofas. Use is often made of grain-free plastic materials which may be transparent or translucent, rather than traditional woods or metals, again for the purpose of avoiding all ornamentation or display other than that imparted by the basic geometric form.

Numerical indications and moving hands afford a mechanistic time display which runs counter to the modern decorative trend and to some degree is also superfluous. Because the typical observer has long been conditioned to read time in terms of position along a scale, numerical indicia are not essential. Moreover, while one must be informed as to the hour, minute and second, to know the exact time, as a practical matter in a domestic environment, such information is more than necessary, for it is quite sufficient to read time in 5-minute increments. For this reason, many household clocks designed for their decorative appeal only mark the 5-minute increments.

SUMMARY OF INVENTION

In view of the foregoing, it is the primary object of the invention to provide a clock in the form of a column having a linear time scale in which the passage of time is indicated by the position and color of an illuminated panel along the face of the column.

More specifically, it is an object of the invention to provide a time column in which the passage of time is linearly related in 5-minute intervals utilizing 11 illuminated color positions to afford a constant progression of hue and form relationships.

A significant feature of the invention is that the linear time column has a severe, pure geometric form, free of hands or numerical indicia, in which time indicia are derived from the position and color of the panel which is indexed along the face of the column.

While a novel display in accordance with the invention entails some degree of reconditioning in reading time, this is easily acquired, in that the time display, though perhaps mysterious to the uninitiated, is perfectly clear and aesthetically satisfying to the knowledgeable owner.

Briefly stated, in one embodiment of the invention, these objects are accomplished in a column having a translucent face, behind which is disposed a stack of 11 cells of equal size, each having bulbs therein which are selectively energized by an electrical control circuit operated by a timer. The arrangement is such that the cells are sequentially illuminated

in a manner whereby the hours 1 to 11 are indicated by cells 1 to 11 respectively, going from top to bottom of the column, whereas the 12th hour, (noon or midnight), is indicated by again illuminating the sixth cell, the distinction between the 6th and 12th hour being established by a difference in color. Five-minute increments, which are 11 in number, running from 5 minutes to 55 minutes, are indicated by sequentially illuminating cells 1 to 11 but in a color distinct from the hour indications.

10 In another embodiment of the invention, the minute display is effected by a separate column having 11 cells standing next to the hour column to provide a twin column system.

BRIEF DESCRIPTION OF DRAWINGS

15 For a better understanding of the invention as well as other objects and further features thereof, reference is made to the following detailed description to be read in conjunction with the accompanying drawing, wherein:

20 FIG. 1 is a perspective view of a single system linear time column in accordance with the invention;

FIG. 2 schematically shows the arrangement of light bulbs in the cells of the column;

25 FIG. 3 is a schematic diagram of the electrical circuit for energizing the bulbs in a timed sequence; and

FIG. 4 is a perspective view of a double linear column in accordance with the invention.

DESCRIPTION OF INVENTION

30 Referring now to FIG. 1, there is shown a linear time column in accordance with the invention, the column 10 having a rectangular cross section and being provided with a translucent face 11 made of a dark-grey plastic material, preferably an acrylic such as Plexiglas. The column is otherwise opaque and may be of polished stainless steel or similar material. Time is indicated by illuminated light panels such as panels 12 and 13 whose position and color along the column are representative of the passage of time. In the absence of illumination, the face of the column is dark, so that one sees nothing but the particular panel being illuminated.

35 Referring now to FIG. 2, behind the face of the column is a vertical stack of 11 rectangular cells 1 to 11, of equal dimensions. Disposed within cells 1 to 11 on the right side thereof are 11 electric light bulbs BM₁ to BM₁₁ which, in practice, may be green colored, to indicate the passage of minutes in 5-minute increments. Thus, bulb BM₁, when activated, indicates 5 minutes after the hour; bulb BM₂, 10 minutes after the hour and so on to bulb BM₁₁ which indicates 55 minutes after the hour.

40 Disposed in the left side of the cells are bulbs BH₁ to BH₁₁ to indicate the passage of hours I to XI. In practice, these bulbs may all be blue except for bulbs BH₃, BH₆ and BH₉, which are of magenta to highlight the third, sixth and ninth hours. The 12th hour, (noon or midnight), is indicated by bulb BH₁₂ which is disposed in cell 6 between bulbs BH₆ and BH₉.

45 The activation of the bulb is selectively controlled by a suitable electronic or mechanical switching device operated by a timer so that, in the course of each hour, starting a moment after 12-noon or 12-midnight, the following switching actions occur:

50 A. Bulbs BM₁ to BM₁₁ are sequentially energized to provide successive green light indications in cells 1 to 11, indicative of 5-minute, 10-minute, 15-minute, 20-minute, 25-minute, 30-minute, 35-minute, 40-minute, 45-minute, 50-minute and 55-minute intervals.

55 B. At 60 minutes after 12-noon or 12-midnight, blue bulb BH₁ is activated to indicate 1 o'clock.

60 C. Thereafter, bulbs BM₁ to BM₁₁ operate in sequence to indicate 1:05, 1:10, 1:15 and so on to 1:55, whereas at 1:60 blue bulb BH₂ is activated to indicate 2 o'clock. D. At 3, 6 and 9 o'clock, bulbs BH₃, BH₆ and BH₉ which are then activated, have a magenta color to better establish these time periods.

65 E. At 12 o'clock, (noon or midnight), the red bulb BH₁₂ is operated, this bulb appearing in the cell 6 position.

Thus, the hours 6 and 12 are indicated at the midpoint in the column, a color distinction serving to establish the hour in question. The side-by-side colors in each cell may be delineated by a partition which, in effect, divides the color panel into two sectors of different color. Or, the partition may be omitted to cause an overlap of colors in the junction areas. But, in either case, hours and minutes are represented by different colors. In place of bulbs, one may use color cards which are operated electromagnetically or mechanically and are shifted into a visible position at appropriate intervals.

Following are examples of time indications produced by the linear time column using the color code specified previously.

Example 1. Second panel blue — Sixth panel green (2:30)

Example 2. Second panel blue — 11th panel green (2:55)

Example 3. Third panel magenta — No green (3:00)

Example 4. Third panel magenta — First panel green (3:05)

Example 5. Third panel partially magenta, partially green (3:15)

Example 6. Sixth panel magenta — No green (6:00)

Example 7. Sixth panel red — No green (12:00)

An electronic circuit for carrying out the above-described switching operations is shown in FIG. 3 where it will be seen that the hour indicating bulbs BH_1 to BH_{12} each have one end connected to one terminal 14 of an electric power line. The other end of bulbs BH_1 to BH_{12} are connected to the fixed selector contacts S_1 to S_{12} of a stepping mechanism 15 whose movable armature 16 is connected to the other terminal 17 of the power line. Thus, when armature 16 engages contact S_1 , bulb BH_1 is energized, when it engages contact S_2 , bulb BH_2 is energized, etc.

The minute-indicating bulbs BM_1 to BM_{11} are each connected at one end to terminal 14 of the power line, and at the other end to selector contact S_2 to S_{12} of a stepping mechanism whose first contact S_1 is left blank. The movable armature 19 of this mechanism is connected to the other power line terminal 17. Thus, when armature 19 engages contact S_2 , bulb BM_1 is activated, when it engages contact S_3 , bulb BM_2 is activated and so on. Both stepping mechanisms are electromagnetically energized.

Stepping mechanism 18 is operated through a normally closed contact 20 which connects this mechanism across the power line to effect energization thereof, the associated armature 19 being caused to step to the next position when contact 20 is broken.

Contact 20 is operated by a timing motor 21 powered from the line, the motor causing the normally closed contact 20 to open at 5-minute intervals, such that at the beginning of the hour, armature 19 engages contact S_1 , at which point no bulb in the BM_1 to BM_{12} series is activated, but at 5 minutes after the hour, armature 19 is stepped to engage contact S_2 , at which point BM_1 is activated. This stepping action continues at 5-minute intervals until at contact S_{12} , bulb BM_{12} is activated to indicate 55 minutes after the hour.

When bulb BM_{12} is activated, a relay 22 shunted across the

bulb is energized, the relay then acting to open a normally closed switch 23 in series with stepping mechanism 15. Thus, at the conclusion of the 55-minute interval, what occurs at 60 minutes after the hour, relay 22 is deenergized, thereby closing switch 23 and activating stepping mechanism 15, at which point armature 16 is caused to step to one contact (S_1 to S_{12}). Hence, at the conclusion of any hour, as indicated by the deenergization of relay 22, armature 16 steps to operate an appropriate hour bulb. In this manner, after each sequential operation of the minute bulb series BM_1 to BM_{11} , an hour bulb BH_1 to BH_{12} is activated to indicate the next hour.

In FIG. 4, the time display is effected by twin columns 24 and 25, column 24 containing bulbs BH_1 to BH_{12} for the hour display in a stack of 11 cells and column 25 containing bulbs BM_1 to BM_{11} for the minute display in a similar stack of 11 cells. This arrangement functions in the same manner as the single column in FIG. 1, except that the minute bulbs are physically segregated from the hour bulbs.

While there has been shown a preferred embodiment of the invention, it will be obvious that many changes may be made within the scope of the invention. Thus, the switching action called for may be effected by a motor-operated cam whose cyclical rotation activates microswitches to effect the sequential activation of the bulbs. The columns need not have a rectangular cross section and, in practice, other configurations may be used.

I claim:

1. A clock having a linear time display, said clock comprising:
  - A column having a translucent, indicia-free face which is dark in the absence of illumination from behind said face;
  - A stack of 11 equal cells disposed behind said face, each having a colored light bulb, except for the sixth cell which is in the exact middle of the column and has two light bulbs of different color, said bulbs when activated providing illuminated light panels along said face; and
  - Timing means cyclically to activate said bulbs in a sequence wherein the hours 1 to 11 are indicated by the cells 1 to 11 from top to bottom and the 12th hour is indicated by activating the second bulb in the sixth cell.
2. A clock as set forth in claim 1, further including a second set of colored light bulbs in said cells and timing means to operate said light bulbs sequentially from top to bottom to indicate 5-minute increments.
3. A clock as set forth in claim 1, wherein said bulbs for the third, sixth and ninth hours are differently colored from the other bulbs.
4. A clock as set forth in claim 2, wherein said cells are partitioned to separate the hour from the minute bulbs to provide distinct sectors of light on said panels.
5. A clock as set forth in claim 2 wherein said second set of light bulbs are disposed in cells in a separate column parallel to the main column.
